JOHN W. HOMER, OF GREENCASTLE, PENNSYLVANIA.

INSULATOR-KNOB.

1,218,181.

Specification of Letters Patent.

Patented Mar. 6, 1917.

Application filed February 24, 1915. Serial No. 10,313.

To all whom it may concern:

Be it known that I, JOHN W. HOMER, a citizen of the United States, residing at Greencastle, in the county of Franklin and 5 State of Pennsylvania, have invented certain new and useful Improvements in Insulator-Knobs; and I do hereby declare the following to be a full, clear, and exact description of the invention, such as will enable others skilled in the art to which it 10 pertains to make and use the same.

This invention relates to electric conductors, and more especially to insulators; and the objects of the same are to improve the 15 devices heretofore used for holding together the two parts of a porcelain insulator or knob.

The improvement consists particularly in the employment of means for preventing 20 contact of the nail or screw with the porcelain at any point, under all ordinary conditions, and the provision of a cushion over the head of the knob so that when the nail is driven home the impact of the blow will not 25 crack the head. The present invention possesses other advantageous features which will appear from the following specification.

In the drawings:

Figure 1 is a sectional view of this invention complete, and Fig. 2 is a bottom plan view of the insulator with the fiber washer indicated in dotted lines and showing how it centers the nail or screw within the bore of the insulator base.

Fig. 3 is a plan view of one of the fiber washers before it is applied, Fig. 4 shows its application to a nail, and Fig. 5 its application to a screw.

Fig. 6 is an enlarged sectional view 40 through one of the leather washers in place on a screw.

Fig. 7 is a similar view of a slightly modified form of leather washer with slits, and Fig. 8 of another modification of the same.

In the drawings, the numeral 1 designates the top or cap member of the insulator knob, and 2 is the base member thereof, the latter being formed in its lowered end with a recess 3 preferably containing a series of 50 webs 4 whose lower edges incline upwardly and inwardly and preferably have shoulders 5 within their length. These two members or portions of the insulator are usually made of glass, porcelain, or some friable 55 material, and they are provided with aligned bores 6 through which passes a nail 7 or a

screw 8 which is of sufficient length to extend completely through both members so that its point may be engaged with the cross bar of the telegraph pole or the other support on which the insulator is to be mounted. The numeral 9 designates the head of either the nail or the screw, and 10 is its point, the latter being reduced in the case of a nail and threaded for some distance up the shank in 60 the case of a screw. Means are commonly provided such as a socket 11 in one insulator member and a projection 12 on the other for holding these members in strict alignment when assembled; and the present invention is not concerned with the shape of 70 the grooves through or around the insulator or its members and in which lie the electric wires not necessary to show.

In common practice the lineman will 75 carry a number of these insulator knobs in a box or pouch, perhaps a bag slung over his shoulder by a strap; and on reaching the point where one is to be used he climbs the pole to a cross bar and throws his arm over 80 it or around the pole to support himself while at work, and obviously he has not the full and unhampered use of both his hands. Hence it is desirable that when he reaches for an insulator knob one hand can pick up 85 both members of it and the nail which connects them and hold the whole in place while the other hand may drive the nail. I will use the word "nail" to refer to either a nail or screw throughout this specification. 90

Also on his way to work and throughout the day, his time is saved if means are present to keep the two members of every knob and its nail assembled. Therefore provision has heretofore been made for the use of a washer 95 on the shank of the nail below the base member and which will co-act with the head of the nail to perform this duty. This washer is commonly made of paper or fiber and slipped onto the shank of the nail at the time the parts are assembled. I find, however, that the washer often slips off, either while the parts are in the box or perhaps at the moment the lineman is taking out an insulator or about to drive its nail into the cross bar, and the result is considerable loss of time which it is one of the purposes of my invention to economize. Again, if the shank of the nail fits too closely in the bore of the members of the insulator, or the latter be 100 shaken too vigorously, or perhaps dropped, the contact of metal with porcelain will 105

often break one or both members. Finally, the impact of the hammer on the nail head 9 when the tip of the nail is driven home often breaks the cap member 1 or perhaps 5 drives the projection 12 into the socket 11 and breaks the base member 2, again with less of time and materials. It is therefore the specific object of the present invention to overcome these contingencies as far as 10 possible.

By preference I make the shank of the nail 7 or screw 8 smaller than the bore 6 of the members. The paper or fiber washer which I will herein call a "disk" 20 is by 15 preference made of such circumference that it rests on the webs 4 and its periphery fits against the shoulders 5, and the result is that it centers the nail within the bore so that it will take a considerable shock to throw 20 porcelain into contact with metal. I also make use of a rather thick leather disk herein specified as a "washer" 30 as described below, which also may have means as shown in Fig. 7 for centering the upper end of the 25 shank of a nail. The disk 20 while preferably thin, could be thicker than shown herein and could in fact be a duplicate of the washer 30 as to size and material. But I prefer to make it of paper or fiber, and at 30 its center I cut through it a hole 21 which is slightly smaller than the shank 7 of the nail, and then through its body I cut a number of radial slits 22 as best seen in Fig. 3. When this washer is slipped over the point 35 10 of the nail the tongues 23 between said slits bend slightly as seen in Fig. 4, and their curved and blunted inner ends abut against the side of the shank. The result is that when an effort is made to move the latter in 40 the other direction every tongue becomes a brace, its blunted inner end resting against the side of the shank, and the movement of said shank biting against said end rather than slipping past it in this direction so that 45 the tendency is to push the entire tongue radially outward. This action would not occur if it were not for the hole 21; that is to say, if the tongues were strictly triangular their inner ends would be pointed and they 50 would clasp the shank of the nail only by their resiliency. In the use of a screw as seen in Fig. 5, these blunted inner ends of the tongues drop into the grooves or threads, and if the size of the screw and the depth of 55 its threads are in proper proportion to the size of the hole 21, the biting effect of the disk upon the screw is particularly strong.

The leather washer shown in Figs. 6 and 60 7 may have its body 30 made circular or in any other desired shape. It is preferably somewhat thicker than the disk, and I speak of it as leather because that is the material I prefer. It also may have a central hole 31 and radial slits 32, although in this case the 65 hole might be made larger and the slits

omitted. In Fig. 7 I have shown the edge of this washer as undercut at 35, and in Fig. 8 as stepped at 36, for the purpose of illustrating the fact that it could be so shaped as to enter the bore 6 of the cap member 1 and center the nail therein, rather than wholly overlying the upper end of said cap as seen in Fig. 1. Here again the slits 32 could be employed. Or they might be omitted, as the position of this washer (except when it is used in place of the disk) dispenses with the necessity for the clinging action of the tongues on the nail; and even when it is used in place of the disk, its thickness and material will possibly give it sufficient cling. 70 75 80

My improved insulator is assembled by first slipping a washer onto a nail or screw and moving it along the shank and into contact with the head 9 thereof, then applying the caps 1 and the base 2, and finally slipping a disk 20 over the point 10 and along the shank until its periphery rests upon the edges of the inclined webs 4 and fits into the shoulders 5 thereof if said shoulders are employed. The washer and disk now hold the 90 parts from becoming disconnected, and center the nail or screw within the bore 6 so that under all ordinary conditions metal will never touch porcelain. When the line-man applies one of these insulators in the 95 manner above outlined, he has but to pick it out of his box and put it in place with one hand, and then drive on the nail head with a hammer held in the other hand; and if his last blow in sinking the nail should be 100 such as otherwise might cause the head 9 to crack the insulator cap, the presence of a soft washer 30 between these parts prevents that contingency. If a screw 8 be used instead of a nail, the same advantageous results are present. 105

What I claim is:

1. An insulator formed of two members having alined bores, and the lowermost member having a recess in its lower end 110 and radial webs within said recess with upwardly and inwardly inclined lower edges; combined with a fastening device passing through said bores, and a washer on such device and resting on the edges of said 115 webs.

2. An insulator formed of two members having alined bores, and the lowermost member having a recess in its lower end and radial webs within said recess provided 120 with shoulders in their lower edges equidistant from the axial line of this member; combined with a fastening device passing through said bores, and a disk-shaped washer on the shank of said device with its 125 periphery resting in said shoulders, for the purpose set forth.

3. An insulator formed in two members having alined bores, and means on the contiguous faces of said members for holding 130

said bores in registry; combined with a fastening device passing through and appreciably smaller than said bores and having a head at its upper end, means on the fastening device under its head for centering it with respect to the upper end of the bore, a disk on the shank of said fastening device, and means for centering said disk and device with respect to the lower end of the bore and for holding the disk against said lower member.

4. An insulator formed in two members having alined bores, and means on the contiguous faces of said members for holding said bores in registry; combined with a fastening device passing through and appreciably smaller than said bores and having a head at its upper end, a washer under said head, a disk on the shank of said fastening device, and means for centering said disk and device with respect to the lower end of the

the bore and for holding it against said lower member.

5. An insulator formed in two members having alined bores, and means on the contiguous faces of said members for holding said bores in registry; combined with a fastening device passing through and appreciably smaller than said bores and having a head at its upper end, and a washer under 30 said head and reduced at its lower portion to enter the upper end of said bore, a disk on the shank of said fastening device, and means for centering said disk and device with respect to the lower end of the bore and 35 for holding it against said lower member.

In testimony whereof I affix my signature in presence of two witnesses.

JOHN W. HOMER.
